UNITED STATES PATENT OFFICE.

PETE LOPEZ, OF SPARKS, NEVADA.

PENCIL-SHARPENER.

1,262,363.

Specification of Letters Patent. Patented Apr. 9, 1918.

Application filed November 27, 1917. Serial No. 204,263.

To all whom it may concern:

Be it known that I, PETE LOPEZ, a citizen of the United States, residing at Sparks, in the county of Washoe, State of Nevada, have invented a new and useful Pencil-Sharpener; and I do hereby declare the following to be a full, clear, and exact description of the invention, such as will enable others skilled in the art to which it appertains to make and use the same.

The present invention relates to certain new and useful improvements in pencil sharpeners, and has for its object to provide a device of this character which embodies novel features of construction whereby a pencil can be easily and quickly sharpened by applying the pointed end thereof to the sharpener and forcibly pushing downwardly thereon, there being no handles or other mechanism to be manually operated.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a side elevation of a pencil sharpener constructed in accordance with the invention.

Fig. 2 is a vertical longitudinal sectional view through the same.

Fig. 3 is a horizontal sectional view on the line 3-3 of Fig. 2.

Corresponding and like parts are referred to in the following description and indicated in all the views of the drawings by the same reference characters.

Referring to the drawings, which illustrate one embodiment of the invention, the numeral 1 designates a flat bottomed receptacle which forms the base for the pencil sharpener, the sides of the receptacle being returned inwardly at their upper edges and inclined downwardly, as indicated at 2, thereby providing a comparatively small opening through which the pencil shavings can enter the receptacle, and an annular pocket 3 within which they will be collected and held in such a manner that they can not be blown out by a draft of air and will not be scattered if the pencil sharpener is accidentally overturned. A tubular stand-

ard 4 projects upwardly from the center of the receptacle, the interior thereof being formed with a helical groove 5.

A plunger 6 is slidable up and down within the tubular standard 4, said plunger being formed with a helical rib 7 which engages the helical groove 5 of the standard and cooperates therewith to produce a rotary motion of the plunger as it is moved up and down. The upper end of the plunger is formed with an annular flange 6^a and terminates in a stem 6^b to which the inverted conical head 8 of a pencil sharpener is secured. The usual slot 9 is provided in one side of the sharpening head, and a knife blade 10 is secured to the sharpening head in such a manner that the cutting edge thereof projects into the slot, thereby providing for sharpening the point of a pencil which is inserted into the sharpening head when there is a relative rotary motion of the sharpening head and pencil. The lower end of the sharpening head 8 may be secured to the upper extremity of the plunger 6 in any suitable manner, as by means of the set screw 11, while the upper end thereof has a pencil receiving collar 12 connected thereto. Spring arms 13 may be provided at the upper end of the collar 12 for releasably gripping the sides of the pencil.

A guide sleeve 14 is slidable upon the exterior of the standard 4, the upper end of the guide sleeve being bent inwardly and crimped at 15 in such a manner as to obtain a loose bearing on the flange 6^a of the plunger, thereby enabling the plunger to turn freely independently of the sleeve. Surrounding the plunger and housed within the sleeve is a coil spring 16, the lower end of the coil spring bearing against the standard 4, while the upper end thereof engages the inwardly bent end 15 of the sleeve. When the plunger is moved downwardly the spring 16 is compressed, said spring serving to return the plunger to its original position as soon as pressure thereon is released. In this connection it may be noted that the upper edge of the sleeve is bent inwardly and received loosely between the sharpening head 8 and flange 6^a of the plunger so that the sleeve and plunger must move up and down in unison, although the plunger is free to rotate independently of the sleeve.

Surrounding the sleeve 14 and sharpening head 8 is an outer tubular shell 17, said shell having a spaced relation to the mem-

bers and serving to direct the shavings and dust from the pencil downwardly into the receptacle without permitting them to be scattered or accumulate around the plunger 5 in such a manner as to clog the same and interfere with the free action thereof. This outer guide shell may be supported in position in any desired manner, as by means of the radial arms 18 between the lower end 10 thereof and the sleeve 16, and the upper end thereof is shown as bent inwardly and downwardly to provide a flange 19 which surrounds and has a slightly spaced relation to the pencil engaging collar 12 of the 15 sharpener. If desired, the sleeve 14 and shell 17 may be held against rotation by means of a screw 20 which operates loosely within the slots 21 in the said members. This screw may also coöperate with the ends 20 of the slots to limit the up and down movements of the plunger.

In using the device the point of the pencil to be sharpened is inserted in the sharpening head 8 and the plunger 6 forced downwardly by applying pressure to the pencil. The collar 12 with the spring arms 13 grips the lower end of the pencil, while the sharpening head 8 and plunger 6 are caused to rotate by the engagement of the helical rib 30 7 of the plunger with the helical groove 5 in the tubular standard 4. The rotation of the sharpening head 8 causes the cutting edge of the knife 10 to sharpen the pencil in the usual manner, the shavings and dust being discharged through the slot 9 and directed by the outer casing 17 into the receptacle 3. As soon as the pencil is removed the plunger 6 will be returned to its original position by the action of the spring 35 16. The outer casing or shell 17 may be provided with a side opening 25 which is normally closed by a door 26. The screw 11 is accessible through this opening, and the opening may also be utilized to remove 40 accumulations of shavings from within the shell, should this become necessary.

Having thus described the invention, what I claim as new and desire to secure by Letters Patent, is:—

50 1. A pencil sharpener including an upright tubular standard having a helical groove therein, a plunger slidable within the tubular standard and formed with a helical rib which engages and coöperates 55 with the helical groove to rotate the plunger when it is moved longitudinally in the standard, a sleeve slidable upon the exterior of the standard and loosely engaging the upper end of the plunger, a coil spring 60 surrounding the plunger and housed within the sleeve and acting to normally hold the plunger at the upper limit of its movement, a pencil sharpening head applied to the upper end of the plunger and arranged co-

axial therewith, and an outer tubular casing 65 surrounding the standard and sharpening head and spaced therefrom, said tubular casing serving to receive the shavings and direct them downwardly away from the sharpening head.

70 2. A pencil sharpener including a receptacle, an upright tubular standard projecting from the base of the receptacle and having a helical groove therein, a plunger slid- 75 able within the tubular standard and formed with a helical rib which the engages and coöperates with the helical groove to rotate the plunger when it is moved longitudinally in the standard, a sleeve slidable upon the exterior of the standard and loosely engag- 80 ing the upper end of the plunger, a coil spring surrounding the plunger and housed within the sleeve, said coil spring serving to normally hold the plunger at the upper limit of its movement, a pencil sharpening head 85 applied to the upper end of the plunger and arranged coaxial therewith, and a tubular casing surrounding the sleeve and sharpening head and spaced therefrom, said tubular casing serving to receive the shavings from 90 the sharpening head and direct them into the receptacle.

95 3. A pencil sharpener including a receptacle, an upright tubular standard projecting from the base of the receptacle and having a helical groove therein, a plunger slid- 100 able within the tubular standard and formed with a helical rib which engages and coöperates with the helical groove to rotate the plunger when it is moved longitudinally in the standard, a slotted sleeve slidable upon the exterior of the standard and loosely engaging the upper end of the plunger, a coil spring surrounding the plunger and housed within the sleeve, said spring serv- 105 ing to hold the plunger normally at the upper limit of its movement, a pencil sharpening head applied to the upper end of the plunger and arranged coaxial therewith, a tubular casing carried by the sleeve, said 110 casing surrounding the sleeve and sharpening head and being spaced therefrom so as to receive the shavings and direct them into the receptacle, and a pin projecting laterally from the standard and loosely received 115 within the slotted portions of the sleeve and casing to prevent rotation and limit the up and down movements thereof.

120 4. A pencil sharpener including a receptacle, an upright tubular standard project- 125 ing from the base of the receptacle and having a helical groove therein, a plunger slid- able within the tubular standard and formed with a helical rib which engages and coöperates with the helical groove to rotate the plunger when it is moved longitudinally in the standard, said plunger having an an- nular flange at the upper end thereof, a

pencil sharpening head applied to the upper end of the plunger and arranged coaxial therewith, a sleeve slidable upon the exterior of the standard and provided at its upper end with an inwardly extended flange which loosely engages the flange of the plunger and has the edge thereof received between the said flange and the lower end of the sharpening head, a coil spring surrounding the plunger and housed within the sleeve, said spring normally serving to hold the plunger at the upper limit of its movement, and means carried by the sleeve for receiving the shavings from the sharpening head and directing them into the receptacle. In testimony whereof I have signed my name to this specification in the presence of two subscribing witnesses.
